DESIGN FOR A CORNER RANGE

Herman H. Heidbreder, Quincy, Ill., assignor to
Excelsior Stove and Manufacturing Co., Quincy,
Ill.

Application August 6, 1934, Serial No. 52,847

Term of patent 7 years

To whom it may concern:

Be it known that I, Herman H. Heidbreder, a citizen of the United States and a resident of the city of Quincy, county of Adams, and State of Illinois, have invented a new, original, and ornamental Design for a Corner Range, of which the following is the specification, reference being had to the accompanying drawing, forming a part thereof.

The figure is a perspective view of my corner range showing the flush construction where the stove top joins the front and ends. The back panel has its ends also ornamentally rounded.

I claim:

The ornamental design for a corner range as shown and described.

HERMAN H. HEIDBREDER.
